UNITED STATES PATENT OFFICE.

DAN J. KAVANAGH, OF NEW MARTINSVILLE, WEST VIRGINIA.

SIGNAL-LOCK.

1,074,955.

Specification of Letters Patent.

Patented Oct. 7, 1913.

Application filed April 25, 1912. Serial No. 693,159.

To all whom it may concern:

Be it known that I, DAN J. KAVANAGH, a citizen of the United States, residing at New Martinsville, in the county of Wetzel and State of West Virginia, have invented certain new and useful Improvements in Signal-Locks, of which the following is a specification, reference being had to the accompanying drawings.

10 This invention comprehends certain new and useful improvements in signaling devices or indicators, designed for use in connection with telephone booths, vehicles, or other inclosures to indicate whether the same are 15 occupied and the door leading thereto is locked.

The invention has for its primary object a simple, durable and efficient construction of device of this character, the parts of 20 which may be cheaply manufactured and readily assembled and not liable to get out of order and which will so operate that the indicating device will be automatically moved to a predetermined position indicating that the inclosure has been vacated or 25 the door leading thereto unlocked, all hanging or accidental setting of the device to the "locked" position being positively precluded. And the invention also aims to 30 generally improve this class of devices to render them more useful and commercially desirable.

With these and other objects in view as will 35 more fully appear as the description proceeds, the invention consists in certain constructions, combinations and arrangements of the parts that I shall hereinafter fully describe and claim.

For a full understanding of the invention 40 reference is to be had to the following description and accompanying drawings in which—

Figure 1 is a perspective view illustrating one application of my improved signal lock; 45 Fig. 2 is a sectional side elevation of the operating mechanism partly broken away; Fig. 3 is a transverse sectional view on the line 3—3 of Fig. 2; Fig. 4 is a similar view on the line 4—4 of Fig. 2; Fig. 5 is a horizontal section on the line 5—5 of Fig. 2; and Fig. 6 is a detail vertical section on the line 50 6—6 of Fig. 2.

Corresponding and like parts are referred 55 to in the following description and indicated in all the views of the accompanying drawings by like reference characters.

Referring to the drawings, the numeral 1 designates a portion of a wall of an inclosure of any character, and 2 a door controlling the opening into said inclosure or compartment. Secured to the inside of the wall 1 is a lock casing 3 which is provided with a journal bearing 4 in which a spindle 5 is mounted, said spindle extending through the wall 1 to the outer side thereof, and provided with a square or other many sided outer extremity whereby a suitably formed key may be attached thereto to operate the device from the outside of the inclosure. A latch lever 6 is mounted intermediate its ends on the spindle 5 to turn therewith, said latch lever being formed within the casing 3 with a preferably angularly disposed arm 7 which is formed with a slot 8 accommodating a pin 9 which is secured to the lower bifurcated end 10 of a vertically disposed and reciprocatory link rod 11, said rod being mounted for movement within a vertically disposed casing 12 the lower end of which is mounted in a bearing sleeve 13 projecting upwardly from the casing 3 and the upper end of which is mounted in and held by a corresponding sleeve 14 carried by a bracket or plate 15 which is secured to the wall 1 in a relatively elevated position above the casing 3. The link rod 11 passes upwardly through the sleeve 14 as clearly illustrated in the drawings, and is provided at its upper end with a forked connecting member 16 carrying a pin 17 which is mounted for movement in a slot 18 formed in one end of a laterally extending arm 19 secured to a horizontally disposed shaft 20 which is mounted in a bearing collar 21 formed on and projecting outwardly from the outer face of the plate or bracket 15. The shaft is also journaled in a bearing ring 22 which is secured by screws or similar fastening devices to the outer side of the wall 1, the shaft projecting outwardly from said wall and having secured to its free extremity or end the semaphore or indicating device 23 which in the present instance is formed of sheet steel with two disks arranged at right angles to each other, one disk being painted white, for instance, and the other disk red, the red disk displaying the word "Locked" and the white disk displaying the word "Unlocked," or being left blank, if desired. A torsion spring 24 is coiled around the shaft 20 and mounted within a cylindrical casing 25, one end of said spring being secured to the bear-

ing ring 22 and the other end of said spring being secured to the shaft 20 as for instance, through the instrumentality of one of the disks of the semaphore. The semaphore may 5 be secured to the shaft in any desired way. At this point it will be understood that the spring 24 exerts its tension to turn the shaft 20 in a direction to bring the white disk of the semaphore to a vertical position which 10 will indicate that the door leading into the inclosure is unlocked.

The forwardly extending arm 26 of the latch lever 6 is provided at its extremity with a finger piece or hand knob 27 and is 15 designed to be swung down into the upwardly facing opening of a keeper 28 secured to the inner side of the door 2. In order to hold the latch lever down in the keeper there is provided a leaf spring catch 20 29 secured to the keeper as shown and so arranged that the lever 6 cannot wedge behind it when being moved downwardly into the keeper.

From the foregoing description in connection with the accompanying drawings, the 25 operation of my improved signaling or indicating apparatus will be apparent.

In the practical use of the device, when 30 the inclosure is entered and the door closed and the latch lever 6 swung down into the keeper 28 to lock the door, it is evident that the spring catch 29 will hold the lever 6 in its locking position and it is also evident that when the lever is swung downwardly, 35 as just stated, its arm 7 will be swung upwardly and thereby move the link rod 11 upwardly and partially rotate the shaft 20 in a direction to bring the red disk to vertical position and the word "Locked" into view, 40 the shaft being rotated against the tension of the torsion spring 24. As soon as the door is unlocked by the disengagement of the latch lever 6 from the keeper 28, the spring 24 will be permitted to act and consequently 45 the shaft 20 will be turned in the reverse direction to automatically shift the position of the semaphore and bring the white disk into a vertical position, said spring 24 effectually precluding any acci-

dental hanging of the parts in this movement and securely maintaining the parts in the required position so long as the latch lever 6 is not engaged with and locked in the keeper 28.

It will thus be seen that I have provided 55 a very positively acting apparatus for the purpose described and one that may be cheaply manufactured and the parts readily assembled and not liable to get out of order.

While the accompanying drawings illustrate 60 what I believe to be the preferred embodiment of my invention it is to be understood that the invention is not limited there to but that various changes may be made in the construction, arrangement and proportions of the parts without departing from 65 the scope of the invention as defined in the appended claim.

Having thus described the invention, I 70 claim:

A signaling device of the character described comprising in combination with a casing and a bracket plate arranged in spaced relation to said casing; bearing sleeves upon said casing and bracket plate 75 respectively, a tubular housing seated at its ends in said bearing sleeves, a rod longitudinally movable through said housing and sleeves, a second bearing sleeve formed upon the bracket plate, a shaft mounted to rotate 80 therein and provided with a signaling semaphore on one of its ends, a spring to yieldingly hold said shaft against rotation, means connecting the opposite end of said shaft to one end of the longitudinally movable rod, 85 an operating lever fulcrumed adjacent one of its ends within said casing, and a connection between said lever and the other end of said rod to move said rod and rotate the semaphore carrying shaft, substantially 90 as and for the purpose specified.

In testimony whereof I hereunto affix my signature in the presence of two witnesses.

DAN J. KAVANAGH.
